Horace C. Wilcox
Inventor
By Atty.
John Earle

UNITED STATES PATENT OFFICE.

HORACE C. WILCOX, OF WEST MERIDEN, CONNECTICUT, ASSIGNOR TO THE MERIDEN BRITANNIA COMPANY, OF SAME PLACE.

DESIGN FOR WAITER.

Specification forming part of Desgn No. **7,192**, dated February 17, 1874; application filed February 5, 1874.
[Term of Patent 7 years.]

To all whom it may concern:

Be it known that I, HORACE C. WILCOX, of West Meriden, in the county of New Haven and State of Connecticut, have invented a new Design for Waiter; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for a table-waiter; and it consists in a waiter having a bail extending over from one edge to the opposite edge, the said bail divided above the waiter, and branching to the right and left to separate points of attachment on the edge of the waiter.

A is the waiter, the form of which is no part of this design. B, the bail, extends over the

waiter from edge to edge. Above the waiter the bail is divided upon both sides, one branch extending to the right, the other to the left, the ends of the branches attached to the edge of the waiter equidistant, or nearly so, from the center line.

The bail may be ornamented to suit the taste or demands of the trade.

I claim as my invention—

The design for waiter, consisting of a waiter, A, with a bail, B, divided above the waiter into branches, the said branches extending down to the edge of the waiter, substantially as herein described, and shown in the accompanying illustration.

HORACE C. WILCOX.
